Patented Feb. 19, 1918.

UNITED STATES PATENT OFFICE.

HARRY P. CARLON, OF WILMINGTON, DELAWARE.

FRAME.

1,256,518.

Specification of Letters Patent. Patented Feb. 19, 1918.

Application filed December 9, 1916. Serial No. 135,989.

To all whom it may concern:

Be it known that I, HARRY P. CARLON, citizen of the United States, residing at Wilmington, in the county of New Castle and 5 State of Delaware, have invented certain new and useful Improvements in Frames, of which the following is a specification.

My invention consists of an improved frame and is particularly designed for holding sheet material. One object of my invention is to provide a frame which will securely hold different sized sheets of paper or other material, and which will include 10 adjustable clamping means which may be readily moved into different positions to clamp and hold the paper or other sheet material so that it can be displayed.

Another object is to make my improved invention of simple construction so that it 15 can be manufactured and sold at a comparatively low cost.

These objects, and other advantageous ends which will be described hereinafter, I attain in the following manner, reference 20 being had to the accompanying drawings in which

Figure 1 is an elevation of my improved frame.

Fig. 2 is an enlarged section on the line 25 *a—a* of Fig. 1.

Fig. 3 is an enlarged fragmentary section on the line *b—b* of Fig. 1.

Fig. 4 is an enlarged fragmentary section on the line *c—c* of Fig. 1, and

Fig. 5 is an enlarged fragmentary section on the line *d—d* of Fig. 1.

Referring to the drawing, the frame proper consists of end sections 1 and 2 to which are joined side sections 3 and 4 to 40 form an elongated rectangular frame. The inner edges of the side sections 3 and 4 are grooved longitudinally as shown at 5 and 6. A batten or beam 7 extends transversely between the side sections 3 and 4 and has tongues or tenons 8 and 9 on its 45 opposite ends which slide within the grooves 5 and 6 so that it will be understood that the batten 7 is slidable from one end of the frame to the other.

50 A clamping strip 10, slightly shorter in length than the width between the grooved edges of the side sections 3 and 4, is hinged to the batten 7 by means of spring-pressed hinges 11. The end sections 3 and 4 are

also grooved at 12 and 13 respectively to 55 permit the insertion of a glass plate partition 14, and strips 15 and 16 are provided to retain the plate within the grooves 12 and 13, but may be removed to permit the plate 14 to be replaced if broken or if it is 60 desired to remove said plate for any other reason, this structure being clearly shown in Figs. 2 to 5 inclusive.

The batten 7 is preferably spaced a small distance from the inner surface of the plate 65 14 as shown at 17, so that said batten will be free to slide without frictional engagement with the plate.

The inner surface of the clamping strip 70 10 is provided with a strip of felt or other soft frictional material 18, and the springs of the hinges 11 operate to move said clamping strip 10 toward the inner surface of the plate 14, so that if a strip of paper or other sheet material, as shown at 19 in Figs. 3 75 to 5 inclusive, is inserted back of the felt strip 18, it will be forced against the plate 14 due to the action of the spring hinges 11.

Furthermore, there will be a resultant twisting action on the batten 7 to jam its 80 tenons or tongues against the sides provided by the grooves 5 and 6, so as to prevent the batten from sliding longitudinally.

The end section 2 has secured to it by 85 spring hinges 20, a second clamping strip 21 (see Figs. 1 and 4). This clamping strip is of similar construction to the clamping strip 10, and is preferably provided with a felt strip 25 on its inner surface for engagement with the opposite end of the paper 90 19 which is placed against the inner surface of the glass plate 14.

The clamping strips 10 and 21 have handles 26 and 27 whereby they may be moved on their respective hinges away from 95 the plate 14 to permit a strip of paper to be placed therebetween. In inserting the sheet of paper or other sheet material within the frame, the clamping strip 21 is first opened and one end portion of said sheet is placed 100 between it and the plate 14. The strip 21 is then released and the spring hinges 20 move it to clamp and hold the sheet to the plate 14. The sheet is then smoothed against the plate 14 throughout its length and the 105 batten 7 is slid longitudinally until the clamping strip 19 is directly over the end portion of the sheet which is oppositely dis-

posed to the end portion which is clamped by the clamping strip 21.

The clamping strip 10 is then released and the hinges 11 actuate it to hold the sheet 5 firmly against the plate 14.

In the several views of drawing, the batten 7 is shown adjacent the end section 1, and when in this position, an extremely long sheet may be held by the clamping strips 10 and 21.

If it is desired to hold a shorter strip, the batten 7 is slid longitudinally within the grooves 5 and 6 toward the end section 2 as above described until the clamping strip 10 15 can be brought into engagement with the end portion of the sheet. It will thus be understood that any length and any size sheet may be securely held by my improved invention.

20 As an auxiliary securing means for the batten 7, I employ in some instances a device which when manually turned, will impart thrust in a longitudinal direction to the batten 7, causing the jamming of the latter at 25 one end against one of the side sections 3 and 4. As illustrated, this device consists of an eccentrically mounted disk 28 which is pivotally supported within a recess 29 in the outer face of the batten 7, said disk being 30 provided with a handle 30, which when turned into one position, causes a portion of the eccentric disk to engage the inner edge surface of the side section 3, such a position being clearly shown in Figs. 1 and 2.

35 When the handle 30 is moved into another position, the disk 28 is moved out of frictional engagement with said latter inner edge surface, and the device has no effect. With my improved frame, a sheet of paper 40 or other material may be securely held in a taut condition and may be written upon or displayed as a sign or for any other purpose desired. Furthermore, the sheet material may be quickly inserted or removed. The 45 glass plate 14 is made transparent so that the surface of the sheet material which is adjacent the inner surface of the glass may be seen through the glass.

I have described the hinges 11 and 12 as 50 being spring-pressed hinges, it being noted that these hinges contain springs which operate to relatively move the leaves thereof, however, I wish it understood that I may employ springs which are mounted independently of the hinges if I so desire, and in each case the springs serve to move the clamping strips 10 and 21 toward the partition 14.

While I have described my invention as 60 taking a particular form, it will be understood that the various parts of my invention may be changed without departing from the spirit thereof, and hence I do not limit myself to the precise construction set forth, but 65 consider that I am at liberty to make such

changes and alterations as fairly come within the scope of the appended claims.

Having thus described my invention, what I claim as new and desire to secure by Letters Patent is:

70 1. The combination of a frame, a transparent plate secured therein within said frame, a clamping strip hinged to the frame, means for automatically moving said clamping strip toward the plate, a batten extending transversely from side to side of the frame and adjustable toward and from said clamping strip, a second clamping strip carried by said batten, and means for automatically moving said second clamping strip toward said plate, said clamping strips being operative to clamp and hold sheet material in engagement with said plate, substantially as described.

80 2. The combination of a frame, a transparent plate secured within said frame, a clamping strip hinged to the frame, means for automatically moving said clamping strip on its hinges toward said plate, the inner sides of said frame having grooves 90 forming a guide-way, a batten having its opposite ends slideable within said grooves, a second clamping strip hinged to said batten, means for automatically moving the clamping strip on its hinges toward said 95 plate, said clamping strips being operative in conjunction with each other to secure sheets of different sizes within said frame and against said plate, substantially as described.

100 3. The combination of a frame, a transparent plate secured within said frame, a clamping strip hinged to the frame, means for automatically moving said clamping strip on its hinges toward said plate, said frame having grooves in the inner faces of its opposite sides forming a guide-way, a batten having its opposite ends slideable within said grooves, a second clamping strip hinged to said batten, means for automatically moving the clamping strip on its 105 hinges toward said plate, and operative on said batten to jam its ends within said grooves, said clamping strips being operative in conjunction with each other to secure 110 sheets of different sizes within said frame and against said plate, substantially as described.

115 4. The combination of a frame, a plate within said frame, a clamping strip hinged to the frame, means for automatically moving said clamping strip on its hinges toward said plate, said frame having grooves forming a guide-way, a batten slideable within 120 said grooves, a second clamping strip hinged to said batten, means for automatically moving the clamping strip on its hinges toward said plate, and operative on said batten to jam the latter within the grooves providing 125 said guide-way, said clamping strips being 130

operative in conjunction with each other to
secure sheets of different sizes within said
frame and against said plate, and additional
means operative to impart thrust to said
5 batten and thereby firmly clamp the latter
to the frame, substantially as described.

In testimony whereof I have signed my

name to this specification in the presence of
two subscribing witnesses.

HARRY P. CARLON.
